UNITED STATES PATENT OFFICE.

JACK E. MESSENGER, OF DES MOINES, IOWA.

FOOT ACCELERATOR.

Application filed July 26, 1926. Serial No. 125,016.

The object of my invention is to provide a foot accelerator wherein actuation of the foot accelerator will not operate any of the parts normally provided for hand operation 5 of the carburetor valve.

Still a further object is to provide a pair of levers mounted on a bracket and arranged to move in unison as a bell crank lever when the carburetor valve is operated by 10 the hand throttle and adapted to move relative to each other when the parts are actuated by the foot.

Still a further object is to provide a toggle lever connection for moving the two levers 15 relative to each other for operating the carburetor valve by the foot.

Still a further object is to provide a foot accelerator adapted to operate independently 20 of the hand throttle and yet when the hand throttle has been advanced for movement of the carburetor valve a certain distance then any operation of the foot accelerator will move the carburetor valve further without having to take up the movement given 25 to the carburetor valve by use of a hand throttle.

Still a further object is to provide a foot accelerator wherein movement of the hand throttle control will not in any way affect 30 or carry with it the foot actuatable member.

With these and other objects in view, my invention consists in the construction, arrangement and combination of the various 35 parts of my device, whereby the objects contemplated are attained, as hereinafter more fully set forth, pointed out in my claims, and illustrated in the accompanying drawings, in which:

Figure 1, is a top plan view of a portion 40 of the automobile engine with my improved foot accelerator mounted thereon and in connection with the carburetor.

Figure 2, is a top plan view of my improved accelerator.

Figure 3, is a side view of the same.

Figure 4, is a view similar to Figure 3 with parts shown in another position.

Figure 5, is a detail sectional view taken 50 on line 5-5 of Figure 3, and

Figure 6, is a sectional view taken on line 6-6 of Figure 2.

In the accompanying drawings I have used the reference numeral 10 to indicate an ordinary automobile engine having a

carburetor 12 thereon operable through the 55 carburetor valve control lever 14.

The control lever 14 is normally connected to a hand throttle control by means of a connecting rod 16. In the use of my foot accelerator the connecting rod or link 16 is 60 disconnected from the lever 14 and connected to a part of my accelerator as I will hereinafter explain.

When the link 16 is connected to the lever 14 and moved in a direction indicated by 65 the arrow 18, then it causes the carburetor valve lever 14 to swing for operation of the carburetor.

My accelerator includes a bracket 20 mounted upon the engine 10 and secured 70 thereto by one of the engine bolts 22. The bracket 20 includes a flange having an opening 24 therein through which the bolt 22 extends.

The bracket 20 further includes a downwardly extending part and a horizontal portion upon which parts of the accelerator proper are mounted. In the installation of the support 20 upon the engine 10 it is arranged at an angle relative to the side of 75 the engine as clearly shown in Figure 1 of the drawings.

Pivots mounted and supported upon the bracket 20 is a lever 26 slightly curved in between its ends as at 28 and this portion 85 practically rests upon the support or bracket 20.

The lever 26 is connected to the support 20 by the rivet or the like 30 whereby pivotal or swinging movement of the lever 26 90 may be had relative to the bracket 20. At the curved portion 28 of the lever 20 I also provide an offset portion 29 whereby one end of the lever is slightly higher than the other.

The end of the lever 26 furthest away from the pivot 30 is formed with an upturned ear or lug 32 having an opening 34 therein. The opening 34 has its side edges 95 bevelled in both directions as at 36.

The part 38 of the link 16 is inserted in the opening 34 of the lug 32 as clearly shown in Figure 2 of the drawings. The normal position of the lug 32 is quite close 100 to the lever 14 and it is an easy matter to simply place the part 38 of the link 16 in the opening 34 formed by the lug 32.

Pivots connected to the free end of the

lever 26 by means of a rivet or the like 40 is the lever 42. The lever 42 has its free end pivotally connected to one end of a short link or rod 44. The rod 44 has its other end inserted through the opening formed in the lever 15 which normally receives the part 38 of the link 16.

In order to have the levers 26 and 42 swing together in unison as a bell crank lever, I provide a stop 46 upon the lever 26 which has a shoulder 48 thereon adapted to be engaged by one edge of the lever 42.

From the construction of the parts just described it will be noted that movement of the link 16 by hand throttle operation in the direction indicated by the arrow 18 will impart swinging movement to the lever 26 and due to the stop 46 will cause the lever 42 to move therewith as though the levers 26 and 42 were fixed and form parts of the bell crank lever.

Movement of the lever 26 imparts movement to the rod 44 in the direction indicated by the arrow 50 and this in turn causes the opening or movement of the lever portion of the carburetor.

The effect of this movement is the same as though the link 16 were directly connected to the lever 14. In order to operate the levers 26 and 42 relative to each other for actuation of the lever 14 by foot control, I provide a pair of toggle levers 52 and 54 which are pivotally connected to the lever 26 and lever 42 respectively.

The two levers 52 and 54 are pivotally connected together by means of a rivet or the like 56. One end of the lever 52 projects beyond the rivet 56 and is provided with an opening 58 in which is mounted one end of a foot actuating rod 60.

The rod 60 may be provided with a downturned end which extends through the opening 58. The rod 60 is of any suitable size and may be bent as at 62 in order to bring it to proper position where it may extend through the floor boards 64 of the automobile 10.

A suitable guide washer 66 may be fastened to the floor through which the member 60 extends. A screw cap or foot piece 68 is mounted upon the upper free end of the member 60. In order to retain the levers 26 and 42 in engagement with each other that is where the lever 42 rests against the stop 46, I use a spring 70 fastened at one end to the lever 52 beyond the pivot point 56 and near the opening 58.

The other end of the spring 70 is anchored to the bracket 20 in any suitable manner. The coil spring 70 mounted as is shown in Figure 2 of the drawings, tends to normally cause the toggle levers 52 and 54 to be closed or dropped towards each other and this in turn pulls the levers 26 and 42 towards each other.

The end of the member 60 in engagement with the lever 52 is practically, positioned just above the pivot connection 30 of the lever 26 and the support or bracket 20, so that the entire number of levers upon the bracket 20 that is levers 26, 42, 52 and 54, may be moved in unison by movement of the link 16 without affecting the member 60.

Movement of the member 60 in the direction indicated by the arrow 72 will cause the two toggle levers 52 and 54 to be spaced apart and due to the connection of the levers 52 and 54 with the levers 26 and 42, it necessarily follows that the two levers 26 and 42 are also spread apart or swung upon the rivet 40 as a pivot.

Movement of the two levers 26 and 42 relative to each other imparts movement to the link or rod 44 and this in turn swings the carburetor lever 14. The connection between the lever 26 and link 16 is such that the lever 26 practically remains stationary and does not move during further actuation of the remainder of the parts of the accelerator.

The lever 42 swings away from the lever 26 when the foot member 60 is moved and the parts assume the position shown in Figure 4 of the drawings.

It will be noted that all of the parts mounted upon the bracket 20 practically swing around the pivot 30 and when moved by the link 16 operate as a fixed unit and when moved by the member 60 operate relative to each other.

The advantage of my foot accelerator resides in the use of the toggle lever connection fastened to the two levers 26 and 42 whereby all of the levers may operate as a fixed unit or operate relative to each other as independent movable parts.

In the practical installation of my device all that is necessary is to fasten the bracket upon the engine block and mount the link or rod 16 in the lever 26 and connect the rod 44 to the carburetor control lever 14.

The foot member 60 is extended through the floor board 64.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. A foot accelerator for carburetors comprising a support, a pair of levers pivotally connected together and mounted on said support and capable of movement independently of each other, toggle levers pivotally connected to said pair of levers, and a foot actuatable member in engagement with said toggle levers for moving them whereby

movement of said pair of levers relative to each other may be made and means of connection between one of said pair of levers and a carburetor valve.

5 2. A foot accelerator for carburetors comprising a support, a pair of levers capable of pivotal movement in fixed relationship and capable of pivotal movement independently of each other, means of connection 10 between one of said levers and the carburetor and means operable by the foot for operating said levers independently of each other, said last means including toggle levers connected to said pair of levers.

15 3. A foot accelerator for carburetors comprising a support, a lever pivoted to said support, a second lever pivoted to said first lever and capable of movement independently of said first lever, a stop on said first 20 lever whereby movement of said first lever will impart movement to said second lever in unison therewith, toggle levers connected to said first and second levers and movable therewith in unison, and a foot actuatable 25 rod for moving said toggle levers for thus imparting movement of said second lever relative to said first lever.

4. A foot accelerator for carburetors comprising a support, a lever pivoted to said support, a second lever pivoted to said first lever and capable of movement independently of said first lever, a stop on said first lever whereby movement of said first lever will impart movement to said second lever 30 in unison therewith, toggle levers mounted on said first and second levers, all of said levers being capable of pivotally moving in fixed relationship on said support.

40 5. A foot accelerator for carburetors comprising a support, a pair of levers pivotally connected together and pivotally mounted upon said support, means for fixing one of said levers relative to the other when one of said levers is moved in one direction whereby said levers operate in unison as a bell crank lever, and toggle levers pivotally connected to each of said levers whereby movement of said toggle levers may impart movement to one of said pair of levers independently of the other.

50 6. A foot accelerator for carburetors comprising a support, a pair of levers pivotally connected together and pivotally mounted upon said support, means for fixing one of said levers relative to the other when one of said levers is moved in one direction whereby said levers operate in unison as a bell crank lever, toggle levers supported by said pair of levers and movable with said pair of levers and means for spreading said toggle levers for imparting movement to one of said pair of levers independently of the other.

60 7. A foot accelerator for carburetors comprising a support, a pair of levers pivotally

connected together and pivotally mounted upon said support, means for fixing one of said levers relative to the other when one of said levers is moved in one direction whereby said levers operate in unison as a bell crank lever, toggle levers supported by said pair of levers and movable with said pair of levers and means for spreading said toggle levers for imparting movement to one of said pair of levers independently of the other, and means for yieldingly holding said toggle levers at one limit of their movement.

70 8. A foot accelerator for carburetors comprising a support, a lever pivoted to said support, a second lever pivoted to said first lever and capable of movement independently of said first lever, a stop on said first lever whereby movement of said first lever will impart movement to said second lever in unison therewith, toggle levers connected to said first and second levers and movable therewith in unison, and a foot actuatable 75 rod for moving said toggle levers for thus imparting movement of said second lever relative to said first lever, and means connected to said support and toggle levers for yieldingly holding said second lever in engagement with said stop.

80 9. A foot accelerator for carburetors comprising a support, a lever pivoted to said support, a second lever pivoted to said first lever and capable of movement independently of said first lever, a stop on said first lever whereby movement of said first lever will 85 impart movement to said second lever in unison therewith, toggle levers connected to said first and second levers and movable therewith in unison, and a foot actuatable rod for moving said toggle levers for thus 90 imparting movement of said second lever relative to said first lever, and means connected to said support and toggle levers for yieldingly holding said second lever in engagement with said stop.

95 10. A foot accelerator for carburetors comprising a support, a pair of levers pivotally connected together and mounted on said support and capable of movement independently of each other, means for causing said pair of levers to operate in unison as a single bell crank lever, toggle levers pivotally connected to said pair of levers, and a foot actuatable member in engagement with said toggle levers for moving them whereby movement of said pair of levers relative to each other may be had and means of connection between one of said pair of levers and a carburetor valve.

11. A foot accelerator for carburetors comprising a support, a pair of levers pivotally connected together and mounted on said support and capable of movement independently of each other, means for causing said pair of levers to operate in unison as a single

bell crank lever, toggle levers pivotally connected to said pair of levers, and a foot actuatable member in engagement with said toggle levers for moving them whereby movement of said pair of levers relative to each other may be had, all of said levers being capable of pivotal movement in fixed relationship to each other on said support.

12. A foot accelerator for carburetors comprising a support, a pair of levers pivotally connected together and mounted on said support and capable of movement independently of each other, means for causing said pair of levers to operate in unison as a single bell crank lever, toggle levers pivotally connected to said pair of levers, and a foot actuatable member in engagement with said toggle levers for moving them whereby movement of said pair of levers relative to each other may be had, all of said levers being capable of pivotal movement in fixed relationship to each other on said support,

and yielding means tending to hold said levers in fixed relationship relative to each other.

13. A foot accelerator for carburetors comprising a support, a pair of levers pivotally connected together and mounted on said support and capable of movement independently of each other, a stop on one of said levers whereby movement of said levers in one direction will cause said levers to move together as a single bell crank lever and movement in another direction will cause said levers to move independently of each other, toggle levers pivotally connected to said pair of levers, and a foot actuatable member in engagement with said toggle levers for moving them whereby movement of said pair of levers relative to each other may be had and means of connection between one of said pair of levers and a carburetor valve.

JACK E. MESSENGER.
